UNITED STATES PATENT OFFICE.

HENRY ELLSWORTH WOOD, OF DENVER, COLORADO.

ORE-CONCENTRATOR.

1,088,050.

Specification of Letters Patent. Patented Feb. 24, 1914.

Application filed May 13, 1913. Serial No. 767,307.

To all whom it may concern:

Be it known that I, HENRY E. WOOD, a citizen of the United States, residing at Denver, in the county of Denver and State of Colorado, have invented certain new and useful Improvements in Ore-Concentrators, of which the following is a full, clear, and exact description.

In processes of and apparatus for the concentration of metalliferous ores in use previous to the invention upon which the present application for Letters Patent is based, the surface film tension of liquids had been taken advantage of under widely varying conditions, for effecting the selective separation of the values from the gangue, the operation being generally conducted in such manner that the metal particles were floated off on the surface film of a body of water into a suitable collecting receptacle, while the sand, crushed rock and earthy particles, penetrating this film, sank beneath the surface of the water, and were allowed to settle therein.

In lieu of carrying the values over a spill-way into a launder or collecting tank by flotation, it has been proposed to lift the surface film with its superincumbent particles from the settling tank by means of a traveling belt and to remove the particles from the belt at a point in their course where they will be deposited in a receptacle from which they may be readily recovered, and to this class of apparatus my present invention relates.

The primary objects of my improvement are to effect the distribution of the finely divided material over the surface of the body of water in such manner that a larger proportion of the values will be sustained upon the surface film, and a better separation of the values from the gangue will result; to provide a better and more efficient device for skimming off or removing the surface film with its load of floating particles from the settling tank, and to more readily and effectively recover the said particles after their removal.

To this end my invention comprises the improvements in the construction of apparatus designed for the purpose stated, which will be described in the following specification and summarized in the claims.

In the accompanying drawings which illustrate the invention in its preferred form—Figure 1 is a vertical central section

of the complete apparatus. Fig. 2 is a diagrammatic illustration on an enlarged scale of the traveling take-off belt and its supports, Fig. 3 is an end view of Fig. 1 with a portion of the side of the settling tank removed, Fig. 4 is a top plan view of the take-off belt and supports, and Fig. 5 is an enlarged detail of a portion of the distributor drum or roller.

In these drawings A designates a settling tank of any suitable construction, tapering toward the bottom where it is provided with a controllable outlet B and provided with any suitable means for maintaining the water at the proper level without disturbing to an injurious extent the surface film.

At one end of the tank A, in suitable bearings extending down below the surface of the water, is mounted a drum or roller C adapted to be rotated by a sprocket chain D from a driving shaft E, which latter represents any source of power available for the purpose. The drum C may be hollow or it may be a solid roll, and its surface is covered with a sheet of corrugated rubber F, the corrugations being substantially triangular in section, preferably slightly less than an eighth of an inch deep, and running in a direction parallel to the axis of the drum. The said drum or roller C is partially submerged in the water with which the tank is kept filled to a predetermined level, and the material or ore to be concentrated is deposited upon its exposed surface by a plate G vibrated by a rod g, connected to an eccentric h, which is rotated by a belt k from a pulley l on the main shaft E. The dry material falls from an adjustable opening in a receptacle or hopper H, supported above the apparatus, upon the vibrating plate G. The details of this feed mechanism are not illustrated, except conventionally, as it is merely typical of any suitable device for the purpose. At or near the opposite end of the tank A a roller I is partially submerged, and constitutes one of the supports for an endless take-off belt K, designed to skim or lift off the surface film with its load of floating particles. The roller I is mounted in a frame L, having pivotal bearings on a shaft M and provided with lugs N carrying set screws O, bearing on the edges of the tank and by means of which the frame will be adjusted to the proper angle. Adjacent to tank A is a second tank P, in which a larger roller R, mounted in frame L, is

105

110

partially submerged. The belt K is preferably composed of 16 oz. canvas duck, and in order that it may be free to travel while the two rollers are properly submerged, it 5 is carried over an idler S mounted on the shaft M between the two rollers.

On the shaft of roller R is a sprocket T, which is driven by a chain D from the shaft of the roller C. Sprockets and chains are 10 employed for driving the several rollers in order to insure the proper relative movements of the same necessary for the best operation of the apparatus.

When the device is in operation the ore, 15 in a dry comminuted state, is fed upon the top of the drum C, which is submerged to within one or two inches of its top. Under these conditions the corrugations take up and carry over an amount of water sufficient 20 to afford a continuous surface film through which the sand and gangue pass into the corrugations, but upon which the values float. These latter proceed with a gentle movement toward the take-off belt, and by 25 the latter they, together with the surface film upon which they are suspended, are taken up, and carried over to the second tank P. To accomplish this properly, the angle of the wall formed by the belt to the point of intersection 30 of the film therewith, must actuate or less than 90 degrees. The roller H should therefore be less than one-half submerged, and the same is true of the roller R, as the water film in unwinding from the belt follows the reverse of the same principle 35 by which it is lifted off from the body of water by the belt. If the water in the tank P is maintained at the proper level, no spray or other means for cleaning the belt will be 40 found necessary.

It is desirable that the surface film with its load of metal particles as it unwinds from the belt K, be floated off into a launder over a lip or spillway W at the edge of tank P, 45 as a small amount of middlings will collect in the tank P beneath the surface of the water and may be periodically drawn off and added to the tailings in the main tank, for wet concentration. In practical use, various other accessories commonly employed 50 with apparatus of this general character will be found, desirable, but as these are well known to those skilled in the art they are not illustrated in detail. Among such 55 devices may be mentioned means for maintaining the water level in both tanks; for maintaining the belt in a flat condition under proper tension and such other purposes

as will be recognized as convenient or necessary by those familiar with the use of such 60 apparatus.

What I claim as my invention is:

1. In an ore concentrator of the kind described, the combination with a settling tank, of a rotating drum or roller submerged to 65 near its top and having a longitudinally corrugated surface, the corrugations being of such form as to carry a continuous surface film and means for depositing in a finely comminuted state upon the exposed 70 portion of the drum, the ore to be concentrated.

2. In an ore concentrator of the kind described, the combination of a settling tank, of a drum or roller submerged to near its top 75 and having a longitudinally corrugated rubber surface, the corrugations being of such form as to carry a continuous surface film, and means for depositing in a finely comminuted state upon the exposed portion of 80 the drum, the ore to be concentrated.

3. In an ore concentrator of the kind described, the combination with a settling tank and means for depositing upon the surface of the water therein a finely comminuted metalliferous ore, of an endless traveling take-off belt, having a surface capable of retaining a water film, means for supporting the belt so that its surface emerges from the water at an angle less 85 than 90 degrees with the surface film thereof, and means for removing from said belt the water film with the superincumbent particles carried thereon.

4. In an ore concentrator of the kind described, the combination of a settling tank, means for depositing upon the surface of the water therein a finely comminuted metalliferous ore, a second tank adjacent to the first, a traveling flexible endless belt, 100 having a surface capable of retaining a water film, and means for supporting the belt so that its surface emerges from the water in the first named tank at an angle less than 90 degrees to the surface film thereof, at a point where the floating particles are directed against the belt, and enters the water in the second tank at a corresponding angle, as and for the purpose set forth. 105

In testimony whereof I affix my signature 110 in the presence of two subscribing witnesses.

HENRY ELLSWORTH WOOD.
